UNITED STATES PATENT OFFICE.

MICHAEL W. MAHAR, OF DAYTON, ASSIGNOR OF ONE-HALF TO STEPHEN CRANE, OF HAMILTON, OHIO.

WINDOW FRAME AND SASH.

SPECIFICATION forming part of Letters Patent No. 257,503, dated May 9, 1882.

Application filed January 21, 1882. (No model.)

To all whom it may concern:

Be it known that I, M. W. MAHAR, of Dayton, in the county of Montgomery and State of Ohio, have invented a new and useful Improvement in Window Frames and Sashes, which improvement is fully set forth in the following specification and accompanying drawings, in which—

Figure 1 is an inside view of a window equipped with my improvement. Fig. 2 is a horizontal sectional view of the same through line *x* of Fig. 1. Fig. 3 is a view, as shown in Fig. 2, with the lower sash partly open. Fig. 4 is an enlarged horizontal sectional view of the hinged part of the sash and frame.

The object of my invention is to provide a means of hinging window-sash to the frame, so that they may be used, as in the ordinary manner, either to be raised or lowered, and be counterbalanced by weights, and, in addition to this old and well-known style, be hinged, so that they may be opened and closed like an ordinary door.

It consists in having one of the sides of the frame provided with a dovetail or **T** groove, or a piece so grooved placed thereon, in which groove is placed a strip having a properly-provided tongue. To this strip the window is hinged, as will be now more fully described in detail.

Referring to the accompanying drawings, A represents the window-frame, constructed in the ordinary manner except that the grooves for the window-strip are not formed therein. Instead thereof strips B B' are secured to the frame within at each side, as shown, in which grooves for the outside strips, D, may be formed.

The strip B is provided with dovetail or **T** grooves C, so as to coincide with the location of the upper and lower window-sash when in position. In these grooves are placed strips F F, having the dovetail or **T** tongues. The strips F are the same length as the window-sash, and fit loosely in the grooves, so that

when the sash H G is hinged at I to the strips F F the strips will slide up and down in the grooves in the sash. The strip B' on the opposite side of the frame has hinged thereto, at the inner side, a strip, E, which, when turned in, secures the sash in place, as shown in Figs. 1 and 2. Fig. 3 shows this strip turned out, so as to permit the sash to swing open. It will be observed that by this arrangement a swinging sash is permitted, while at the same time weights can be attached to the strips F F, as with the ordinary sash. The strips B B' are made separate from the frame, since the strips F must be placed in the grooves C after the frame is completed.

Having described my invention, what I claim is—

1. In a window-frame, the strip, secured within the frame as shown, provided with dovetail or **T** grooves C, to coincide with the position of the sash, in combination with the strip B', having hinged to its inner edge the sash-retaining strip E, substantially as herein shown.

2. In a window-sash, the strips F, secured to the strip B by means of dovetail or **T** tongues working in similarly-formed grooves, and having the window-sash G H hinged thereto, substantially as and for the purpose herein set forth.

3. In a window-sash and frame, the frame having the strip provided with dovetail or **T** grooves C, and the strips B', provided with the hinged retaining strip E, in combination with the strips F, provided with tongues operating in grooves C, having hinged thereto the sash G H, substantially as and for the purpose herein shown.

In testimony that I claim the foregoing I have hereunto set my hand, this 9th day of January, 1882, in the presence of witnesses.

MICHAEL WILLIAM MAHAR.
